United States Patent Office

Des. 214,175
Patented May 20, 1969

214,175

BATHROOM CABINET

Salvatore Roggio, Jr., Philadelphia, Pa., and Robert S. Roggio, Delran, N.J., assignors to Lehman Specialty Company, Philadelphia, Pa., a corporation of Pennsylvania

Filed Apr. 29, 1968, Ser. No. 11,694

Term of patent 14 years

Int. Cl. D6—01

U.S. Cl. D33—16

Fig. 1

Fig. 2

FIGURE 1 is a front perspective view of a bathroom cabinet showing our new design, the doors being in an open position;

FIGURE 2 is another front perspective view thereof;

FIGURE 3 is an elevational view taken from one side thereof, the opposite side being a mirror image of the side shown;

FIGURE 4 is a rear elevational view thereof; and

FIGURE 5 is a bottom plan view thereof.

The dominant features of our design reside in the portions shown in full lines.

We claim:

The ornamental design for bathroom cabinet, as shown and described.
